UNITED STATES PATENT OFFICE.

HARRY W. NEAL, OF INDIANAPOLIS, INDIANA.

DESIGN FOR A REGISTER-SHIELD.

47,541.

Specification for Design.

Patented July 6, 1915.

Application filed February 15, 1915. Serial No. 8,383. Term of patent 14 years.

To all whom it may concern:

Be it known that I, HARRY W. NEAL, a citizen of the United States, residing at Indianapolis, in the county of Marion and State of Indiana, have invented a new, original, and ornamental Design for Register-Shields, of which the following is a specification, reference being had to the accompanying drawing, forming part hereof.

The single figure of the drawing is a perspective view of a register shield embodying my new design, there being end members in each of which is formed a rather long and narrow water pocket opening on both the outer and the inner sides of the wall, each of these end members having an upwardly and forwardly curved rear edge, and a curved deflector plate which rests upon and conforms in shape to these rear edges and connects the two end members, the front upper edge of the deflector plate being curved downwardly and rearwardly.

I claim,

The ornamental design for a register shield, as shown and described.

In witness whereof, I have hereunto set my hand at Indianapolis, Indiana, this twelfth day of February, A. D. one thousand nine hundred and fifteen.

HARRY W. NEAL.
